UNITED STATES PATENT OFFICE.

GRACE LEA HUNT, OF WILKES-BARRE, PENNSYLVANIA.

DESIGN FOR AN INVALID'S COUCH.

47,108.

Specification for Design.

Patented Mar. 16, 1915.

Application filed November 12, 1914. Serial No. 871,802. Term of patent 14 years.

To all whom it may concern:

Be it known that I, GRACE LEA HUNT, a citizen of the United States, residing at Wilkes-Barre, in the county of Luzerne, State of Pennsylvania, have invented a new, original, and ornamental Design for Invalids' Couches, of which the following is a specification, reference being had to the accompanying drawing, forming a part thereof.

The figure is a perspective view of an invalid's couch showing my new design.

I claim:

The ornamental design for an invalid's couch, as shown.

GRACE LEA HUNT.
